Primary Examiner — Mary Shannon Malley*Assistant Examiner* — Olivia Aldin(74) *Attorney, Agent, or Firm* — Casimir Jones, S.C.; Brian F. Bradley(57) **CLAIM**

The ornamental design for a hook rail, as shown and described.

DESCRIPTION

FIG. 1 is a perspective view showing my new design of a hook rail;

FIG. 2 is a front view thereof;

FIG. 3 is a rear view thereof;

FIG. 4 is a top view thereof;

FIG. 5 is a bottom view thereof;

FIG. 6 is a left side view thereof; and,

FIG. 7 is a right side view thereof.

The broken lines depict portions of the hook rail that form no part of the claimed design.

1 Claim, 4 Drawing Sheets(56)
